UNITED STATES PATENT OFFICE

2,591,269

SIGNALING WAND FOR FLASHLIGHTS

Frank Lehoczki, United States Army

Application August 28, 1950, Serial No. 181,864

3 Claims. (Cl. 177—329)

1

The present invention relates to new and useful improvements in flashlight attachments and more particularly to means for providing a transparent tubular member with internal diffused light to form a signalling wand free from blinding or annoying glare.

An important object of the invention is to provide a novel arrangement of light diffusing members enclosed in a transparent tubular body and positioned in the path of the beam of light from a flashlight lamp to form an elongated illuminated wand which may be used as an airplane landing signal, traffic signal, or for other purposes where an anti-glare, illuminated signalling device is needed.

A further object is to provide an attachment for flashlights of this character of simple and practical construction, which is efficient and reliable in use, neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is an enlarged longitudinal sectional view taken on a line 2—2 of Figure 1; and,

Figures 3 and 4 are transverse sectional views taken on the lines 3—3 and 4—4 respectively of Figure 2.

Referring now to the drawing in detail, wherein for the purpose of illustration I have disclosed a preferred embodiment of my invention, the numeral 5 designates a transparent tubular casing having an internal attaching ring 6 cemented in one end of the casing for threading on the outer end of the barrel 7 of a flashlight.

Ring 6 is formed with an inwardly projecting flange 8 engaged behind a transparent disk or lens 9 held against the reflector 10 of the flashlight. An insulation washer 10a spaces the reflector from the barrel 7. The outer end of tubular casing 5 is closed by an opaque end wall or cap 11.

A light diffusing structure, designated generally as 12, is held in the casing 5 between inner disk or lens 9 and outer end wall 11, and comprises a group of inner longitudinal bars 13 of "Lucite" which includes a main bar 14 of a width equal to the internal diameter of member 5 and

2

a pair of relatively narrow bars 15 at opposite sides of bar 14 at its center. A similar group of longitudinal bars 16 is positioned at the outer end of the light diffusing structure 12 against the end wall 11.

Between the inner and outer groups of longitudinal bars 13 and 16 is a group of square shaped "Lucite" blocks 17 positioned one upon the other and with alternate blocks having their corners 18 staggered so that each corner at the opposite surfaces of the blocks as well as at the side edges of the blocks will reflect light passing through the blocks.

The bars of the inner and outer longitudinal groups 13 and 16 as well as the blocks 17 are cemented or otherwise secured to each other to hold the individual members of the diffusing structure in assembled relation.

The vertical edges of the main bars 14 of the inner and outer longitudinal groups are bevelled, as shown at 19, and are alined with the opposite corners 18 of alternate blocks 17.

Light from the lamp of the flashlight will be conducted through the longitudinal bars 13 and 16 and also through the blocks 17 and will be reflected laterally at the sides of the bars and blocks as well as at the opposite surfaces of the corners of the blocks to provide diffused light internally of the transparent casing 5 throughout its entire length.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A flashlight attachment comprising a transparent elongated casing adapted for attaching to the outer end of a flashlight barrel, an opaque end wall closing the outer end of the casing and including inner and outer longitudinal bars and a central group of square shaped blocks positioned in a stacked staggered relation with respect to each other between the inner and outer longitudinal bars to expose part of the surface of each block as well as the side edges of the

blocks, and said bars and said blocks having the property of conducting light subjected to one end of the light diffusing structure by the flashlight for reflecting the light at the flat surfaces of the bars and blocks.

2. A flashlight attachment comprising a transparent elongated casing adapted for attaching to the outer end of a flashlight barrel, an opaque end wall closing the outer end of the casing, and a light diffusing structure in the casing having the property of conducting light and composed of a plurality of units each constructed to provide flat edge portions positioned parallel to the axis of the casing to reflect diffused light from the flashlight at the sides of the casing.

3. A flashlight attachment comprising a transparent elongated casing adapted for attaching to the outer end of a flashlight barrel, an opaque end wall closing the outer end of the

10 casing, and a light diffusing structure in the casing having the property of conducting light and composed of a plurality of units contacting each other and each constructed to provide flat edge portions positioned parallel to the axis of the casing to reflect diffused light from the flashlight at the sides of the casing.

FRANK LEHOCZKI.
